UNITED STATES PATENT OFFICE

109,709

DESIGN FOR A COMBINED WRINGER AND WASHING MACHINE CASING

Ray W. Franklin, Davenport, Iowa

Application September 30, 1937, Serial No. 71,887

Term of patent 14 years

To all whom it may concern:

Be it known that I, Ray W. Franklin, a citizen of the United States, residing at Davenport, in the county of Scott, and State of Iowa, have invented a new, original, and ornamental Design for a Combined Wringer and Washing Machine Casing of which the following is a specification, reference being had to the accompanying drawings, forming part thereof.

Figure 1 is a rear view in perspective of a combined wringer and washing machine casing showing my new design.

Figure 2 is a front view in perspective, and, Figure 3 is a fragmentary view in perspective showing the wringer as it appears when swung away from the machine casing.

I claim:

The ornamental design for a combined wringer and washing machine casing, as shown and described.

RAY W. FRANKLIN.
